UNITED STATES PATENT OFFICE.

CHESTER COMSTOCK, OF BROOKLYN, NEW YORK.

IMPACT AND REACTION MOTOR.

No. 870,867.

Specification of Letters Patent.

Patented Nov. 12, 1907.

Application filed November 24, 1902. Serial No. 132,583. Renewed March 24, 1906. Serial No. 307,921.

To all whom it may concern:

Be it known that I, CHESTER COMSTOCK, a citizen of the United States, residing in Brooklyn, in the county of Kings and State of New York, have invented certain 5 new and useful Improvements in Impact and Reaction Motors, of which the following is a specification.

This invention relates to motors or rotary engines, and it consists substantially in the improvements hereinafter particularly described.

10 The invention has reference more especially to motors or rotary engines of that class or character which are driven or propelled both by direct impingement and reaction of charges of steam or other expansible propulsive agent; and the principal object of the invention is to provide such a motor which is thoroughly reliable and effective in operation, besides being comparatively simple in the construction and organization 15 of parts or elements constituting the same.

A further object is to provide a motor of the kind referred to which is economical both in its production and expenditure of energy; and one in which there is practically no waste or leakage, and in which inertia is readily overcome both in the stopping and starting of the same.

20 Other objects of the invention will hereinafter more fully appear when taken in connection with the accompanying drawings in which:—

Figure 1, is a vertical side elevation of my improved impact and reaction-motor as it appears when constructed for operation; and Fig. 2, is a vertical longitudinal sectional view thereof, showing parts removed and the shaft broken off at the ends. Fig. 3, is a part vertical transverse sectional elevation of Fig. 2. Fig. 4, is a horizontal sectional plan view of the casing and interior construction, certain parts being cut out to more clearly indicate the organization. Fig. 5, is a sectional detail view in perspective to more clearly indicate the construction and organization of the means for effecting the propulsion of the wheel both by direct 30 impingement and reaction of charges of expansible propulsive agent thereupon. Fig. 6, is a similar view to Fig. 4, with the section taken in a different plane, and illustrating more clearly the lateral courses taken by the separate portions of each charge of expansible 35 propulsive agent employed. Fig. 7, is an enlarged horizontal sectional view in detail; and Fig. 8, is a separate view in perspective of each of the several parts constituting the means for effecting the propulsion of the motor, said parts being shown substantially in the 40 relation they bear to each other when properly assembled or combined.

Before proceeding with a more detailed description it may be stated that my improved impact-motor comprises means whereby on admission of charges of an 45 expansible propulsive agent to the motor such charges are caused to flow laterally of the central plane of ro-

tation of the impact-wheel, and the construction and organization of the parts of the motor are such that each charge in transit serves to rotate the impact-wheel both by direct impingement and reaction thereupon. To 60 effect this operation I employ a casing of special interior embodiment, and an impact-wheel also of special embodiment, the two coöperating in an efficient manner to utilize the full force of the charges of expansible propulsive agent without tendency to interruption of 65 the speed of the motor.

Specific reference being had to the accompanying drawings by the designating characters marked thereon, A, represents the casing of my improved impact-motor, the same being stationary and mounted upon a pillar 70 or standard a, having a base b, the said casing comprising a cylinder c, having secured to each end thereof, by means of bolts d, a head or disk e, each of which is formed centrally with a sleeve or stuffing-box f, having a gland g, said latter elements forming bearings for 75 a shaft B, extending through the motor, as shown. Mounted centrally of said shaft, with the ends thereof in working contact with the inner ends of said sleeves or stuffing-boxes f, is the hub h, of an impact-wheel C, having a rim 2, and preferably a connecting web 3, 80 between the rim and hub, said rim being considerably less in diameter than the diameter of the cylinder c, of the casing, and said web having openings l, therein forming communication between the spaces m, m, on either side of the web within the rim, said spaces together constituting an exhaust-chamber for the propulsive agent, after expenditure of its force, a suitable outlet-pipe n, for the exhaust being fitted in one of the heads or disks e, and leading from said chamber. Instead of the web 3, I may employ suitable spokes for 90 connecting the rim with the hub of the impact-wheel, as is apparent, and I may also otherwise construct said wheel without departure from my invention. Fitted rigidly upon the outer surface of the said rim 2, at the center thereof, is a ring 5, having pockets formed there- 95 in at intervals of its outer surface all around, the walls 6, of each of said pockets being preferably parallel to each other and substantially tangential to said outer surface of the ring, see more particularly Figs. 3, and 5, and the walls of each succeeding pocket being in- 100 clined to the walls of the pocket preceding it. Also fitted or rigidly secured upon the outer surface of the rim 2, and on either side of said centrally disposed ring 5, is another ring 7, having in the outer surface thereof similar pockets, the walls 8, of which are flush or in alinement with the said walls 6, of the pockets of said ring 5; and secured to the rim in like manner, and to the outer side of each of said rings 7, is another ring 9, having in the outer surface thereof similar pockets, the walls 10, of which are also flush or in alinement with the 110 walls of the pockets in each of the said rings 7. Still further secured to the outer surface of said wheel-rim,

and to the outer side of each of said rings 9, is another ring 12, similarly constructed and arranged as the several rings already described, the walls of the pockets of each of these rings (12) being designated at 13. Finally, there is also secured to the outer surface of the wheel-rim 2, at the outer side of each of the said rings 12, a ring 15, the width of which is preferably considerably less than the width of either of the other rings described, and the depth or thickness of which is considerably greater than the depth or thickness of the said other rings, each of said outer rings 15, being formed with conduits or ports 16, leading outwardly from each of the pockets of said ring 12, see Figs. 5, 6, and 7. The outer edges of said rings 15, are in movable or working contact with adjacent portions of the inner surface of a cylinder 17, which is fitted in a stationary manner within the casing with the outer surface thereof in contact with the inner surface of the cylinder *c*, of said casing. Rigidly fitted to a portion of the inner surface of said cylinder 17, so as to inclose the ring 5, of the wheel-rim, is a centrally disposed ring 20, the outer surface of which is recessed circumferentially all around so as to form a continuous pressure-chamber 21, for an expansible propulsive agent, said pressure-chamber being in communication through regularly located openings 22, in cylinder 17, with a continuous supply-chamber 23, for such agent, formed in the inner surface of the said cylinder *c*, said supply-chamber having in communication therewith the inner end of a supply-pipe 24, leading from a source (not shown) from which the expansible propulsive agent is derived. At regular or predetermined intervals thereof the body of said ring 20, is formed with injector-ports 25, the sides of which are inclined inwardly substantially at right angles to the walls of the pockets of the several rings hereinbefore described, said injector-ports extending all the way through such ring-body, as shown. The width of said ring 20, is substantially equal to the width of the said ring 5, and the inner surface of the ring 20, is formed with pockets corresponding in location and number with the pockets in ring 5, the sides 26, of the pockets of said ring 20, being also inclined and substantially parallel with each other. Also rigidly secured to the inner surface of the cylinder 17, of the casing, and at each side of the said ring 20, is a ring 27, the width of which is in excess of the width of each of the rings 7, and formed in the inner surface of each of said rings 27, all around is a series of pockets constructed precisely the same as the pockets in said ring 20, the walls of the pockets of these rings (27) being indicated at 28. Similarly secured to the said inner surface of cylinder 17, and at the outer side of each of said rings 27, is still another stationary ring 29, the width of which is in excess of the width of each of the rings 12, and the inner surface of which is formed with pockets corresponding in number and position to the pockets of rings 20, and 27, the outer edges of said rings 29, having the adjacent surfaces of the rings 15, in working contact therewith, and the walls of the pockets therein being designated at 30. It will of course be understood that the number of movable and stationary rings employed may be reduced or increased, as desired, and it will be seen that when the wheel is in position to have the pockets of the several rings thereof register with the pockets of the rings on the interior of the casing a number or series of

chambers are thus formed extending from end to end of the inner structure. Seated in a circular recess 31, therefor in the inner face of each head or disk *e*, of the casing is a stationary ring 33, formed with pockets constituted each of an inclined wall 34, and a straight radially disposed wall 35, said pockets corresponding in number to the pockets hereinbefore referred to in connection with the different movable and stationary rings employed, it being observed that the height of each of said recesses is in excess of the depth or thickness of each of said rings 33, thus leaving an open space all around the inner edge of said ring through which the spent charges of expansible propulsive agent pass into the exhaust-chamber *m*, *m*, and thence outwardly through the exhaust-pipe.

Located between the adjacent sides of each of the rings 7, and 9, on the rim of the wheel is a comparatively narrow ring 35^a, the depth or thickness of which all around is equal to the depth or thickness of each of the rings first named, thus forming a partial or semi-partition to the longitudinal chambers formed by the sides of the pockets of the two series of rings, as is apparent, each of said partitions being intermediate the sides of each of the stationary rings 27, of the cylinder 17; and similarly located between the adjacent sides of each of the said rings 9, and said rings 12, is another comparatively narrow ring 37, of equal depth or thickness with the first, and forming another partial or semi-partition for the said chambers, each of these latter rings occupying a position substantially intermediate the sides of each of the stationary rings 29, of cylinder 17. Located between the adjacent sides of each of the stationary rings 27, and 29, of said cylinder 17, is also a comparatively narrow ring 40, the depth or thickness of which is about equal to the depth or thickness of said first-named rings (27 and 29), thus also forming a partial or semi-partition to said chambers, these latter partial or semi-partitions being intermediate those formed by the said narrow rings 35 and 37, as shown. In this way portions of the charges of the expansible propulsive agent which are forced through the injector-ports of ring 5 by pressure are caused to flow laterally on opposite sides of the central plane of rotation of the impact-wheel, substantially as indicated by the arrows shown in Fig. 6.

In the operation of the motor the pressure-chamber formed in the outer surface of ring 5, is kept constantly filled with the expansible propulsive agent under pressure, and charges of such agent are caused to be injected through said injector-ports, as is apparent, and the end walls of the pockets in the stationary rings of cylinder 17, constitute abutments or resistances whereby the impact-wheel is turned or propelled by direct impingement of the charges upon the end walls of the rings on the wheel-rim, such impingement first taking place in the pockets of ring 5, where the main or initial force of impact of the charges is expended. While thus expending such force the charges successively received in the pockets of said ring 5, spread laterally of their own expansion and flow in opposite directions with respect to the central plane of rotation of the wheel, and the separate portions of such charges pass over and under the partitions formed by the several narrow rings described, substantially as indicated, and in transit these charge-portions continue to act by impingement

and reaction upon the end walls of the pockets of the rings on the wheel-rim, until finally the said charge-portions pass into the exhaust-chamber through the conduits or ports in the rings 15, on the rim, and the 5 straight or radially disposed walls of the pockets of the stationary rings 33, serve as abutments or resistances by which the wheel C is further assisted to be propelled by reaction of the charge-portions, as will be fully understood.

10 As shown in Fig. 1, the shaft B is also supported in outer bearings 50, at the upper ends of standards or uprights 52, said shaft being provided with a pulley 53, for suitable connection therewith of a belt to be driven from the motor.

15 It will be understood that various changes or alterations may be made in the form or embodiment herein shown without departure from the spirit or scope of my invention.

It will be noted that I have provided a rotating member within a casing, and that upon this rotating member I have located a plurality of rings each two of which is divided by partitions which extend outward from the periphery of the rotating member. In like manner the interior of the casing is also provided with rings 20 and partitions which are so located as to come between, substantially about midway, the partitions herein first mentioned. All of these partitions are of substantially equal length, as for instance seen in Fig. 2 of the drawings. All of the rings aforementioned are provided 25 with recesses, which are preferably inclined, and these recesses form series of rows of courses through which the propulsive agent must pass. The arrangement of the partitions as hereinbefore specified is such as to render the course irregular or wavy so as to force the propulsive 30 agent up and down or sidewise in its travel through the course.

Having thus described my invention, I claim:—

1. An impact motor comprising a casing, a shaft, a 40 rotating member carried thereby and means for rotating said member both by impact and reaction of a propulsive agent thereupon, said means consisting of a series of rings affixed to said casing, and a series of rings affixed to said member, all of which rings have corresponding recesses in their adjacent surfaces forming thereby steam courses, 45 and semi-partitions between each two rings whereby the force of the propulsive agent is alternated from one series of rings to the other.

2. An impact motor comprising a casing, a shaft, a 50 rotating member carried thereby, and means for rotating said member by alternated direct and reacting impacts of a propulsive agent thereupon, said means consisting of a plurality of members affixed to said casing and a plurality of members affixed to said member, all of which members have corresponding recesses in their adjacent 55 surfaces forming thereby steam courses, and semi-partitions between each two members whereby the course of the propulsive agent is deflected and thereby alternated from one series of members to the other.

3. An impact motor comprising a casing, a shaft, a 60 member carried thereby and means for rotating said member by alternated direct and reacting impacts of a propulsive agent thereupon, said means consisting of a series of rings affixed to said casing and a series of rings affixed to said member, all of said rings having corresponding 65 recesses in their adjacent surfaces forming thereby rows of steam courses, and semi-partitions located in each of said rows whereby the course of the propulsive agent is deflected and thereby alternated from one series of the rings to the other series.

70 4. An impact motor comprising a casing, a shaft, a rotating member carried thereby and means for rotating

said member by alternated direct and reacting impacts of a propulsive agent thereupon, said means consisting of a series of rings affixed to said casing and a series of rings affixed to said member, all of which rings have corresponding inclined recesses in their adjacent surfaces thereby forming steam courses and semi-partitions between the rings whereby the course of the propulsive agent is deflected and caused to alternate from one series of rings to the other series.

75

5. An impact motor comprising a casing, a shaft, a wheel carried thereby and means for rotating said wheel both by impact and reaction of a propulsive agent thereupon, said means consisting of a series of rings affixed to the casing and a series of rings affixed to said wheel, all of said rings having corresponding recesses in their adjacent surfaces forming thereby a series of steam courses, and semi-partitions between the rings whereby the course of the propulsive agent is deflected so as to alternate from one series of rings to the other.

80

6. An impact motor comprising a casing, a shaft, a rotating member carried thereby and means for rotating said member both by impact and reaction of a propulsive agent, said means consisting of a series of rings affixed to said casing, and a series of rings affixed to said member, said last mentioned rings being coincident with and lateral to the central plane of rotation of said member and having corresponding recesses in their adjacent surfaces forming thereby steam courses, and semi-partitions between said rings whereby the course of the propulsive agent is deflected and alternated from one series of rings to the other.

90

7. An impact motor comprising a casing, a shaft, a rotating member carried thereby and means for rotating said member both by impact and reaction of a propulsive agent, said means consisting of a series of rings affixed to said casing, and a series of rings affixed to said member, said last mentioned rings being coincident with and lateral to the central plane of rotation of said member and having corresponding inclined recesses in their adjacent surfaces forming thereby steam courses, and semi-partitions between said rings whereby the course of the propulsive agent is deflected and alternated from one series of rings to the other.

100

8. An impact motor comprising a casing, a shaft, a rotating member carried thereby and means for rotating member by alternated direct and reacting impacts of a propulsive agent thereupon, said means consisting of a series of rings affixed to said casing and a series of rings affixed to said member, said last mentioned rings being coincident with and on opposite sides of the central plane of rotation of the wheel and having corresponding recesses in their adjacent surfaces forming thereby steam courses, and semi-partitions between said means whereby the course of the propulsive agent is deflected and altered 125 nated from one series of rings to the other.

110

9. An impact motor comprising a casing, shaft, a rotating member carried thereby and means for rotating said member by alternated direct and reacting impacts of a propulsive agent thereupon, said means consisting of a series of rings affixed to said casing and a series of rings affixed to said member, said last mentioned rings being coincident with and on opposite sides of the central plane of rotation of the wheel and having corresponding inclined recesses in their adjacent surfaces forming thereby steam courses, and semi-partitions between said means whereby the course of the propulsive agent is deflected and alternated from one series of rings to the other.

135

10. An impact motor comprising a casing, a shaft, a rotating member carried thereby and means for rotating said member by alternated direct and reacting impacts of a propulsive agent thereupon, said means consisting of a series of rings affixed to said casing and a series of rings affixed to said member, said last mentioned rings being coincident with and lateral to the central plane of rotation of the wheel and having corresponding recesses in their adjacent surfaces forming thereby steam courses, and semi-partitions between said means whereby the course of the propulsive agent is deflected and alternated from one series of rings to the other.

145

11. An impact motor comprising a casing, a shaft, a

150

- rotating member carried thereby and means for rotating said member by alternated direct and reacting impacts of a propulsive agent thereupon, said member consisting of a series of rings affixed to said casing and a series of rings affixed to said member, all of said rings having corresponding recesses in their adjacent surfaces forming thereby steam courses, and semi-partitions between the rings and disposed in alternation in opposite directions in the course whereby the travel of the propulsive agent is deflected and alternated from one series of rings to the other. 5
12. A cylinder having impact recesses upon its periphery and a casing having co-operative impact pockets upon its inner periphery and at its ends, a hollow cylinder having impact recesses upon its periphery and a casing having co-operative recesses upon its inner periphery and upon its ends, means for enabling the exhaust steam to exhaust at each end into the hollow of said cylinder, and an exhaust port communicating with said hollow. 15
13. An impact motor comprising a casing, a shaft, a member carried thereby, means for rotating said member by alternated direct and reacting impacts of a propulsive agent thereupon, said means constituting a series of rings carried by the casing and a series of rings carried by a movable member, the rings of the two series having corresponding recesses in their adjacent surfaces forming thereby steam courses, semi-partitions between each two rings whereby the force of the propulsive agent is alternated from one series of rings to the other, outer movable rings having ports corresponding to said chambers and stationary rings on the end of said casing each forming means for final impingement of the charges thereupon. 20
14. An impact motor comprising a casing, a shaft, a member carried thereby, means for rotating said member by alternated direct and reacting impacts of a propulsive agent thereupon, said means constituting a series of rings carried by the casing and a series of rings carried by a movable member, the rings of the two series having corresponding recesses in their adjacent courses forming thereby steam courses, semi-partitions between each two rings whereby the force of the propulsive agent is alternated from one series of rings to the other, outer movable rings having ports corresponding with said chambers and stationary rings on the ends of the casing having recesses therein, each formed with an inclined and a straight wall. 25
15. An impact-motor comprising a casing, a shaft, a wheel rigid with the shaft, means for rotating said wheel by impact of charges of an expansible propulsive agent thereupon, said means being constituted of a series of rings rigid with the casing and a series of rings movable with the wheel, the rings of the two series having corresponding pockets in their adjacent surfaces, forming thereby chambers, alternating semi-partitions extending into said chambers, outer movable rings having ports corresponding with the chambers, and stationary rings on the ends of the casing each formed with means for final impingement of the charges thereupon. 30
16. An impact-motor comprising a casing, a shaft, a wheel rigid with the shaft, means for rotating said wheel by impact of charges of an expansible propulsive agent thereupon, said means being constituted of a series of rings rigid with the casing and a series of rings movable with the wheel, the rings of the two series being coincident with and lateral to the central plane of rotation of the wheel, and having corresponding pockets in their adjacent surfaces, forming thereby chambers, alternating semi-partitions extending into said chambers, outer movable rings having ports corresponding with the chambers, and stationary rings on the ends of the casing having pockets therein each formed with an inclined wall and a straight wall. 35
17. An impact-motor comprising a casing, a shaft, a wheel rigid with the shaft, means for rotating said wheel by impact of charges of an expansible propulsive agent thereupon, said means being constituted of a series of rings rigid with the casing and a series of rings movable with the wheel, the rings of the two series being coincident with and on opposite sides of the central plane of rotation of the wheel, and having corresponding pockets in their adjacent surfaces, forming thereby chambers, alternating semi-partitions extending into said chambers, outer movable rings having ports corresponding with the chambers, and stationary rings on the ends of the casing, outer mov- 40
- able rings having ports corresponding with the chambers, and stationary rings on the inner ends of the casing having pockets therein each formed with an inclined wall and a straight wall. 45
18. An impact-motor comprising a casing, a shaft, a wheel rigid with the shaft, means for rotating said wheel by impact of charges of an expansible propulsive agent thereupon, said means being constituted of a series of rings rigid with the casing and a series of rings movable with the wheel, the rings of the two series being coincident with and lateral to the central plane of rotation of the wheel, and having corresponding inclined pockets in their adjacent surfaces, forming thereby chambers, alternating semi-partitions extending into the chambers on opposite sides thereof, outer movable rings having ports corresponding with the chambers, and stationary rings on the inner ends of the casing having pockets therein each constituted of an inclined wall and a straight wall. 50
19. An impact-motor comprising a casing, a shaft, a wheel rigid with the shaft, means for rotating said wheel by impact of charges of an expansible propulsive agent thereupon, said means being constituted of a series of rings rigid with the casing and a series of rings movable with the wheel, the rings of the two series being coincident with and on opposite sides of the central plane of rotation of the wheel, and having corresponding pockets in their adjacent surfaces, forming thereby chambers, alternating semi-partitions extending into said chambers from opposite sides thereof, outer movable rings having ports corresponding with the chambers, and stationary rings on the inner ends of the casing having pockets therein each constituted of an inclined wall and a straight wall. 55
20. An impact motor comprising a casing, a shaft, a drum rotatably mounted thereon and means for rotating said drum both by impact and reaction of a propulsive agent thereupon, said means consisting of a series of rings affixed to said casing, and a series of rings affixed to said drum, all of which rings having corresponding recesses in their adjacent surfaces forming thereby steam courses, and semi-partitions between each two rings whereby the force of the propulsive agent is alternated from one series of rings to the other. 60
21. In an impact motor, the combination with a rotatable member and an opposed member, of a passage between said rotatable and said opposed members for a propulsive agent, and a plurality of impact surfaces alternating upon said rotatable member and said opposed member comprising a series of impact surfaces substantially tangential of said rotatable member, and a succeeding series of impact surfaces radially of said rotatable member. 65
22. In an impact motor, the combination with a rotatable member and an opposed member, of a plurality of impact rings affixed to said opposed member, a plurality of impact rings affixed to said rotatable member and staggered relatively to said impact rings on said opposed member, a plurality of partition rings interposed between said impact rings on said opposed member and projecting into working contact with said impact rings on said rotatable member, and a plurality of partition rings interposed between said impact rings on said rotatable member and 70 projecting into working contact with said impact rings on said opposed member, said impact rings provided with impact surfaces substantially tangential of said rotatable member. 75
23. An impact motor comprising a casing, a shaft a drum rotatably mounted thereon, and means for rotating said drum by alternated direct and reacting impacts of a propulsive agent thereupon, said means consists of a plurality of members affixed to said drum, all of which members have corresponding recesses in their adjacent surfaces forming thereby steam courses, and semi-partitions between each two members whereby the course of the propulsive agent is deflected and thereby alternated from one series of members to the other. 80
24. An impact motor comprising a casing, a shaft, a drum rotatably mounted thereon and means for rotating said drum by alternated direct and reacting impacts of a propulsive agent thereupon, said means consisting of a series of rings affixed to said casing and a series of rings affixed to said drum, all of said rings having correspond- 85

- ing recesses in their adjacent surfaces forming thereby rows of steam courses, and semi-partitions located in each of said rows whereby the course of the propulsive agent is deflected and thereby alternated from one series of the 5 rings to the other series.
25. In an impact motor, the combination with a rotatable member and an opposed member, of a series of impact rings affixed to said opposed member, a series of impact rings affixed to said rotatable member, said impact 10 rings having impact surfaces substantially tangential to said rotatable member, and current diverting partition rings interposed between said impact rings in part affixed to said opposed member, and in part affixed to said rotatable member.
- 15 26. In an impact motor, the combination of a substantially cylindrical casing, heads inclosing said casing, a rotatable member mounted within said casing to rotate in bearings in said heads, a cylindrical lining for said casing, an annular chamber formed between said casing and 20 said lining, and rings affixed to the inner surface of said lining and provided with a plurality of ports substantially tangential to said rotatable member and a plurality of impact surfaces upon its inner surface substantially tangential to said rotatable member, a plurality of impact rings 25 affixed to the inner surface of said lining and provided with impact surfaces upon their inner surfaces substantially tangential to said rotatable member, a plurality of impact rings affixed to said rotatable member and staggered with relation to said impact rings on said opposed 30 member, and provided upon their outer surfaces with impact surfaces, partition rings disposed between said impact rings on said opposed member and projecting into working contact with said impact rings on said rotatable member, partition rings disposed between said impact 35 rings on said rotatable member projecting into working contact with said impact rings on said opposed member, a partition ring or rings affixed to said rotatable member remote from said ported ring, said last named partition ring or rings provided with spirally directed ports, impact 40 rings provided with substantially radial impact surfaces and affixed to said heads opposite said spirally directed ports, communication from said radial impact surfaces to an exhaust, and a supply communicating with said annular chamber and ports in said ported ring.
- 45 27. In an impact motor the combination with a rotatable member and a stationary member, of a passage for a propulsive agent the path of which is transverse to the direction of travel of the rotatable member, a plurality of escape orifices in said rotatable member from said passage directed backwardly of the direction of motion of 50 said rotatable member, and a plurality of impact surfaces on said opposed member radial of said rotatable member and disposed before said orifices and so arranged as to alternate the flow from one side to another along the 55 passageway.
28. An impact motor comprising a casing, a shaft, a drum rotatably mounted thereon, and means for rotating said drum by alternated direct and reacting impacts of a propulsive agent thereupon, said means consisting of a 60 series of rings affixed to said casing and a series of rings affixed to said drum, all of which rings have corresponding inclined recesses in their adjacent surfaces thereby forming steam courses and semi-partitions between the rings whereby the course of the propulsive agent is deflected and caused to alternate from one series of rings to the other 65 series.
29. A hollow cylinder having rings upon its periphery and forming impact pockets and a casing also provided with rings forming co-operative impact pockets upon its 70 inner periphery, means for enabling the exhaust steam to escape into the hollow of said cylinder, and an exhaust port communicating with said hollow.
- 75 30. A cylinder having impact pockets upon its periphery, and a casing having co-operative impact pockets upon its inner periphery, means for enabling the exhaust steam to escape at 31. A hollow cylinder having rings upon its periphery forming impact pockets, and a casing provided with rings forming co-operative impact pockets upon its inner periphery, means for enabling the exhaust steam to escape at 80 each end into the hollow of said cylinder, and an exhaust port communicating with said hollow.
32. A cylinder having impact pockets upon its periphery and jets upon each end, and a casing having co-operative impacts upon its inner periphery and at its ends.
33. A hollow cylinder having impact pockets upon its periphery and jets upon each end and a casing having co-operative impact pockets upon its inner periphery and at each end, means for enabling the exhaust steam to escape at each end into the hollow of the cylinder, and an exhaust port communicating with said hollow.
34. An impact motor comprising a casing, a wheel rotatably mounted thereon and means for operating said wheel both by impact and reaction of a propulsive agent thereupon, said means consisting of a series of rings affixed to the casing and a series of rings affixed to said wheel, all of said rings having corresponding recesses in their adjacent surfaces forming thereby a series of steam courses, and semi-partitions between the rings whereby the course of the propulsive agent is deflected so as to alternate from one series of rings to the other.
35. An impact motor comprising means for transmitting power and means for operating said means both by impact and reaction of a propulsive agent, said second means consisting of a series of rings affixed to one member and a series of rings affixed to another member, said last mentioned rings being coincident with and lateral to the central plane of rotation of said members and having corresponding recesses in their adjacent surfaces forming thereby steam courses, and semi-partitions between said rings whereby the course of the propulsive agent is deflected and alternated from one series of rings to the other.
36. An impact motor comprising rotatably mounted means for transmitting power, and means for rotating said means both by impact and reaction of a propulsive agent, said second means consisting of a series of rings affixed to one member, and a series of rings affixed to a member, said last mentioned rings being coincident with and lateral to the central plane of rotation of said members and having corresponding recesses in their adjacent surfaces forming thereby steam courses, and semi-partitions between said rings whereby the course of the propulsive agent is deflected and alternated from one series to the other.
37. An impact motor comprising a power transmission means rotatably mounted and means for rotating said transmission means by alternated direct and reacting impacts of a propulsive agent thereupon, said second means consisting of a series of rings affixed to one member and a series of rings affixed to another member, said last mentioned rings being coincident with and on opposite sides of the central plane of rotation of the wheel and having corresponding recesses in their adjacent surfaces forming thereby steam courses, and semi-partitions between said means whereby the course of the propulsive agent is deflected and alternated from one series of rings to the other.
38. An impact motor comprising rotatably mounted power transmission means, and means for rotating said transmission means by alternated direct and reacting impacts of a propulsive agent thereupon, said second means consisting of a series of rings affixed to one member and a series of rings affixed to another member, said last mentioned rings being coincident with and on opposite sides of the central plane of rotation of the wheel and having corresponding inclined recesses in their adjacent surfaces forming thereby steam courses, and semi-partitions between said means whereby the course of the propulsive agent is deflected and alternated from one series of rings to the other.
39. An impact motor comprising rotatably mounted power transmitting means and means for rotating said means by alternated direct and reacting impacts of a propulsive agent thereupon, said second means consisting of a series of rings affixed to one member, and a series of rings affixed to another member, said last mentioned rings being coincident with and lateral to the central plane of rotation of the wheel and having corresponding recesses in their adjacent surfaces forming thereby steam courses, and semi-partitions between said means whereby the

course of the propulsive agent is deflected and alternated from one series of rings to the other.

40. An impact motor comprising power transmission means, and means for operating the same by alternated direct and reacting impacts of a propulsive agent there-upon, said means consisting of a series of rings affixed to one and of rings affixed to another member, all of said rings having corresponding recesses in their adjacent surfaces forming thereby steam courses, and semi-partitions 5 between the rings and disposed in alternation in opposite directions in the course whereby the travel of the propulsive agent is deflected and alternated from one series of rings to the other.

41. A cylinder having impact pockets upon its periphery and jets upon each end, a casing provided with rings 15 forming coöperative impact pockets upon its inner periphery, means for enabling the exhaust steam to escape at each end into said cylinder, and an exhaust port communicating with said cylinder.

Signed at Nos. 9-15 Murray st., New York, N. Y., this 20
20th day of November, 1902.

CHESTER COMSTOCK.
